EXPANSION-COIL FOR REFRIGERATING SYSTEMS.

1,352,964.

Specification of Letters Patent. Patented Sept. 14, 1920.

Application filed January 5, 1918. Serial No. 210,435.

To all whom it may concern:

Be it known that we, CLARENCE M. HOLLEY and FLOYD W. ROBISON, citizens of the United States, residing at Detroit, county 5 of Wayne, State of Michigan, have invented a certain new and useful Improvement in Expansion-Coils for Refrigerating Systems, and declare the following to be a full, clear, and exact description of the same, such as 10 will enable others skilled in the art to which it pertains to make and use the same, reference being had to the accompanying drawings, which form a part of this specification.

This invention relates to expansion coils 15 for artificial refrigerating systems, and its primary object is to provide a unit construction for coils of such character whereby a coil of any desired capacity may be built up for use with refrigerator boxes of varying capacity by simply securing together 20 as many units as may be required in a manner to operate as a continuous coil. Another object of the invention is to provide a unit for the construction of a composite coil of 25 several units, each unit being formed of a coiled tube so arranged that the inlet and outlet are on opposite sides, and when assembled with other units, positioned respectively adjacent the ends of the contiguous 30 units with the inlet of one unit connected with the outlet of the other by a U bend. By this arrangement, the several units are formed in one continuous coil, having an inlet and an outlet at opposite ends adapted 35 for connection with the supply and return pipes of the expansion system, means being provided for fixedly holding the coils in a stack. These objects and the several novel features of the invention are hereinafter 40 more fully described and claimed and shown in the accompanying drawings in which—

Figure 1 is a plan view of a coil involving our invention.

Fig. 2 is a side elevation of several units 45 connected together to form a composite coil.

As will be understood from Fig. 1, each unit consists of a tube 1 having an inlet at 2. This tube is formed in a flat coil, the first 50 turns 1, 3 and 5 being spaced a distance apart sufficient to allow the return bent portion 6 and 7 to be inserted therebetween, the coil being formed in an S bend as indicated

at 8 centrally of the coil. The coils, as is well known, carry the expanding fluid (as ethyl chlorid or sulfur dioxid), which 55 enters the tube 1 at the end 2 and is discharged therefrom at the end 9 after having made the circuit of the coil as described.

These unit coils are to be connected in a stack one over the other as indicated in Fig. 60 2 in which the coil *a* is connected with the coil *b* which in turn is connected with a coil *c*. The inlet and outlet ends of the tubes are enlarged as is indicated in the drawings to receive a U bend 10 connecting one coil 65 with the other to form a continuous coil for circulation of the expanding fluid.

With the coils superimposed as stated, a retainer 11 is used between each coil and having the arms 12, 13 and 14 on opposite 70 ends as indicated in Fig. 1 adapted to receive the securing bolts 15 passing through the ends of the arms. By means of the nuts 16 the coils are fixedly held in position and the assembled sections of the coil may be 75 handled as a unit. U bends 10 connect the discharge end of one coil with the inlet end of the other coil as will be readily understood and are sweated into place providing a fluid tight joint. 80

It is evident from the above description that a coil of any desired capacity may be formed by assembling the desired number of units *a*, *b*, or *c*, and by formation of the coil in flat form as described and connected 85 together in the manner stated, a coil comparatively inexpensive in character is provided without necessity of revision of form for coils of various sizes and a uniform and standard construction is secured by the described arrangement in units. 90

Having thus briefly described our invention, what we claim and desire to secure by Letters Patent of the United States is—

1. An expansion coil for artificial refrigerating systems comprising a series of units 95 connected together to form a continuous coil, each unit consisting of a return-coiled tube, the coil being formed by bending of the tube in the desired form to the center and the 100 return coils being positioned between each of the first turns whereby, in adjacent turns of the coil, fluid flows in opposite directions, the ends of the completed coil terminating

on adjacent sides thereof and being connected with the adjacent ends of the contiguous coils.

2. An expansion coil for artificial refrigerating systems consisting of a series of units connected together to form a continuous coil, each unit consisting of a return flat-coiled tube, the ends thereof terminating on adjacent sides of the coil and each end being connected with the adjacent end of a contiguous coil on opposite sides thereof, the composite coil thus formed having an inlet at one end and an outlet at the other, and means for securing the units in superimposed relation.

3. An expansion coil for artificial refrigerating systems consisting of a series of units connected together to form a continuous coil, each unit consisting of a return flat-coiled tube, each end thereof being connected respectively with the ends of a contiguous coil on opposite sides, the two terminal coils

of the series being adapted for connection with the supply and return pipes of the expansion system.

4. An expansion coil for artificial refrigerating systems consisting of a series of units connected together to form a continuous coil with the ends thereof adapted for connection respectively with the supply and return pipes of the system, each unit consisting of a return flat-coiled tube, the ends thereof terminating on adjacent sides of the coil and each end being connected respectively with the adjacent end of the contiguous coil on opposite sides, and a spacer member extending between each unit, the spacer members adapted to be secured together to bindingly engage the said units.

In testimony whereof we sign this specification.

CLARENCE M. HOLLEY.
FLOYD W. ROBISON.
